UNITED STATES PATENT OFFICE

ARNOLD M. SKUDRE, OF WEST NEWTON, MASSACHUSETTS, ASSIGNOR TO SUBMARINE SIGNAL COMPANY, OF BOSTON, MASSACHUSETTS, A CORPORATION OF MAINE

COMPENSATOR SWITCH

Application filed August 31, 1929. Serial No. 389,726.

The present invention relates to an electrical switching mechanism in which it is necessary to adjust carefully the timing and operation of the switch, and more particularly to electric compensator switches which are used in submarine signaling to determine the direction of a source of sound.

In systems for the determination of a source of sound, an electric compensator is often used in connection with a plurality of sound receiving devices. In such a system, the electric compensator connects between the listener's telephones and the sound pick-up device elements to retard the progress of the sound a definite amount so that the sounds from the various receivers coming to the listener's source arrive there at the same time. Since the velocity of sound in water is about 4800 feet per second, the increments of retardation are very small in such a device. They usually are of the order of microseconds.

The compensator switch in such cases functions to insert these increments in various receiver lines until the impulses arrive together at the ears of the observer or at the indicating device. The insertion is usually in such a manner that the direction of the source can be directly read off from a scale as the switch is turned by having the scale associated with the switch. While the insertion of these elements of retardation creates a definite lag, irrespective of when the switch contacts may be closed, the reading of the compensator will not be accurate unless the closing or opening of the switch occurs when the relative position of the switch and scale is what it should be.

If, therefore, the contact does not open and close to insert and take out elements of retardation when the switch and the indicator associated with it are at the right position with reference to the scale, the measurement will be in error, even though the retardation elements are accurate.

In the electric compensator of the type described in the present invention, a roller is brought under the arm of each switch contact. This action raises the arm and breaks the contact at a definite position of the roller

and indicator associated therewith. The present invention makes it a simple proposition to adjust the contacts so that this will occur at the desired time. Where the assembly of compensators employing this type of switch formerly was a very exacting process and needed the most skilled help, the assembly using the present invention is comparatively simple.

The invention will now be described in connection with the drawings, in which

Figure 1 shows a plan view,

Figures 2 and 3 a detail side view, and

Figure 4 shows the switch elements in circuit.

In Figure 1 is shown an insulating disc 1, on which is mounted uniformly about a circumference the switch contact arms 2 and 3, as indicated in the figure. The contacts 5 and 6 on the respective arms are normally closed, but may be opened when the roller 7 raises the upper contact arm 3. The roller 7 is mounted on a rotatable shaft 8, concentric with the circumference of the switch contacts mentioned above. This shaft carries also the wiping contact arms 9 and 10, which lead to the indicator or listener's telephone from either side of the contact which is broken, and connect through the contact 13 and the bracket 11 to the lower contact arm 2.

In this manner, the indicator is connected in circuit from points on both sides when the line 14 is opened. In this system it is usual to have the impulses coming from both ends of the line, as shown in Figure 4, where at both ends there is an input, which may be the microphones 15 and 16, and for the indicator to be connected at the point where the line is broken. If, therefore, the line is broken more towards one end than the other, there is less retardation in the shorter section. As the break is shifted, the retardation in one section is increased as the other side is diminished.

As shown in Figure 1, there is provided a scale 17, which rotates with the roller 7, and also a stationary indicator 18. The direction of the source of sound is marked as the scale rotates with the roller by the relative position of the indicator and scale.

The arms 2 and 3 are somewhat resilient and bear against one another through the contacts 5 and 6 with a certain pressure. As the roller comes beneath the arm 3, the latter is raised, but the contact between 5 and 6 is not immediately broken, because the arm 2 follows and rises with the arm 3. The contact, however, must be broken before the arm 3 has been raised its maximum, as otherwise it could not positively be broken at all. 10 The position of the roller at which the contact is broken is dependent, therefore, upon the pressure between the two contact arms. This pressure is definitely adjustable by 15 means of the screw 12 through the hole 19 to give the arm 2 just the right tension.

When the arm 3, therefore, is raised by the movement of the roller 7, the contacts 5 and 6 begin definitely to rub against one another and at a definite position of the roller 20 7 the contact is broken. This definite position fixes the reading of the indicator on the scale within the accuracy of the line of error.

In the present system it is, therefore, not necessary to bend the spring arms and adjust and bend until the proper tension is obtained. It is only necessary to adjust the screw 12 which may be done without removing any of the elements. Moreover, the adjustment may be accurately and quickly made. 25

Having now described my invention, I claim:

1. In an electric compensator for connecting retardation elements between receivers and indicators, a group of switch contacts, means for opening said switch contacts successively to vary the amount of retardation connected between the indicators and the receivers, a scale and pointer associated with said means to locate the position of said means, and resilient means normally maintaining said switch contacts closed and means adjusting the tension on said resilient means whereby the point of opening of said contacts may be adjusted. 35

2. In an electric compensator for connecting retardation elements between receivers and indicators, a switch comprising two resilient contact arms, a substantially non-resilient support adjacent one of said arms and adjustable means supported in said support and adapted to exert a tension on said arm by the adjustment thereof. 40

3. In an electric compensator for connecting retardation elements between receivers and indicators, a switch comprising two resilient contact arms, a substantially non-resilient support adjacent one of said arms, and means making contact with said arm and adjustable in said support for exerting the desired tension on said arm. 45

4. In an electric compensator for connecting retardation elements between receivers and indicators, a switch comprising two re-

silient contact arms, a substantially non-resilient support adjacent to one of said arms, a screw passing through said arm and adjustable in said support to exert the desired tension on said arm. 50

5. In an electric compensator for connecting retardation elements between receivers and indicators, a group of switch contacts, means for opening said switch contacts successively to vary the amount of retardation connected between the indicators and the receivers, a scale and pointer associated with said means to locate the position of said means, said switch contacts being mounted on resilient arms, a substantially non-resilient support adjacent one of said arms, and adjustable means tensioning said arm to said support to adjust the relative position of opening of said contact and said first named means. 55

In testimony whereof I affix my signature.

ARNOLD M. SKUDRE.
